UNITED STATES PATENT OFFICE

103,001

DESIGN FOR A REFRIGERATOR

Everett Worthington, Chicago, Ill., assignor to The Coca-Cola Company, Wilmington, Del., a corporation of Delaware

Application December 3, 1936, Serial No. 66,292

Term of patent 14 years

To all whom it may concern:

Be it known that I, Everett Worthington, a citizen of the United States and resident of Chicago, Cook County, Illinois, have invented a new, original, and ornamental Design for Refrigerators, of which the following is a specification, reference being had to the accompanying drawings, forming part thereof.

Fig. 1 is a front perspective view of the refrigerator, embodying my new design;

Fig. 2 is a top plan view;
Fig. 3 is a side elevational view; and
Fig. 4 is an end elevational view thereof.

I claim:

The ornamental design for a refrigerator as shown.

EVERETT WORTHINGTON.
